ACTION FOR PIPE ORGANS

Filed June 3, 1931

UNITED STATES PATENT OFFICE

CASPER ELDRED GRANT, OF PORTSMOUTH, VIRGINIA

ACTION FOR PIPE ORGANS

Application filed June 3, 1931. Serial No. 541,896.

This invention relates to an action for pipe organs and is designed for operating air valves in wind chests, for shifting relay switches, and for other purposes.

5 It is an object of the invention to provide a magnet of novel construction having sufficient power on a low voltage to open a valve against wind pressures which ordinarily have been considered high in organ constructions, 10 which has not been possible of accomplishment with apparatus heretofore employed.

Another object is to utilize a valve action which is free of springs, is formed of the minimum number of parts, and produces an 15 extensive but abrupt movement of the actuated part.

A still further object is to provide an efficient action which operates on a low voltage so that a low voltage can be used throughout 20 the organ structure and danger of arcing at the various contacts in the organ is eliminated with a consequent reduction in fire hazards.

With the foregoing and other objects in view which will appear as the description proceeds, the invention resides in the combination and arrangement of parts and in the details of construction hereinafter described and claimed, it being understood that changes in the precise embodiment of the invention 30 herein disclosed may be made within the scope of what is claimed without departing from the spirit of the invention.

In the accompanying drawing the preferred form of the invention has been shown.

35 In said drawing:

Figure 1 is a section through a portion of a pipe organ equipped with the present invention.

40 Figure 2 is a section on line 2—2, Figure 1.

Figure 3 is a view of a modified structure.

45 Figure 4 is a section on line 4—4, Figure 1. Referring to the figures by characters of reference, 1 designates a wind chest for holding the series of valve actions whereby the flow of air to the pipes is controlled. These pipes, one of which has been shown at 2, are mounted at their lower ends on a rest 3 provided with ports 4 for conducting air to the respective pipes. Each of these pipes can be 50 held in a sleeve 5 carried by a standard 6 or

any other desired supporting means can be used.

A valve 7 is provided for each port and is connected to and operated by a hanger 8. The upper end of the hanger is pivotally connected by pointed bearing studs 9 to an arm 10 fixedly mounted in the wind chest 1 above port 4. An integral core 11 extends downwardly from arm 10 and carries the coil 12 of an electromagnet. 55

The lower free end of core 11 is beveled as shown at 13 and extending into close proximity thereto is an arcuate armature 14 formed integral with hanger 8 and arranged in an arc concentric with the pivot 9 so as to travel across the end of the core and remain very slightly but uniformly spaced therefrom. 60

The free end of armature 14 has a V-shaped recess 15 providing spaced terminal points 16 which normally lie close to the armature as shown in Figure 2 so as to be well within the magnetic field. 65

The hanger 8 is a part of the armature and is limited in its movement by a button 17 carried by a pin 18. Normally however, the weight of the armature and the valve will maintain the valve in closed position across port 4 where it will be held tightly by the wind pressure in the chest 1. 70

75 When the coil is energized the armature 14 will be pulled in the direction of its length and as some of the metal of the armature is removed at the free end due to the formation of recess 15, the tendency of the magnet will be to pull the armature in the direction of its length rather than transversely thereof, this pulling action increasing as the apex of

the recess approaches the center of the core 11. As a result of this action it has been found that with a low voltage the magnet will operate to open valve 7 against what have been considered high wind pressures. The advantage residing in the use of a low voltage 80

85 is the reduction of danger of arcing at the various contacts in an organ structure and consequent reduction of fire hazard. It has been impossible, as far as I am aware, until now to use as little as ten volts in a valve 90 action. 95

While this electro-magnet construction is particularly useful as a valve operating means, it is to be understood that it can also be used as a relay and for other purposes in the mechanism of the organ. For example, and as shown in Figure 3, a contact 17 can be insulated from but carried by the armature 18 and pulled against two or more yieldable terminals 19 for closing a circuit there-

10 through.

Obviously other changes can be made in the construction of the device. The number of coils can be increased and they can be arranged in any suitable manner for further 15 increasing the power of the magnet while still retaining the important features hereinbefore enumerated, namely, the arcuate armature and the recess in the end thereof.

It will be noted that the armature is mounted 20 on pointed pivot studs 9. This gives a freely movable hanger type of armature which is very desirable because of its firm bearing and ease of movement.

Obviously different types of valves can be 25 used to meet the different demands and it is not intended that the invention be limited to the form of valve shown.

What is claimed is:

1. In an action for pipe organs an electro-
30 magnet including a core, an armature electrically connected to one end portion of the core and mounted to swing relative thereto, said armature being concentric with its point of connection and movable close to and across 35 the other end of the core, there being a V-shaped recess extending into the free end of the armature the sides of which are substantially tangent to the core and converge 40 away from the core to the apex of the recess, said recess providing spaced ends normally close to the sides of the core adapted gradually to enter the field of the armature when energized thereby to exert a pull of maximum 45 strength longitudinally of the armature.

2. In a pipe organ construction the combination with a wind chest having an outlet port, of means for controlling the flow of air through the port from the chest, including an arm, a core extending therefrom, a hanger 50 pivotally connected to the arm and extended downwardly therefrom, an armature integral with the hanger and supported close to and movable across one end of the core, said armature and end of the core being substantially 55 concentric with the axis of movement of the hanger, a magnet coil on the core, and a valve on the hanger normally closing the port by gravity, said armature having a V-shaped recess extending into the free end 60 thereof, the edges of said recess being substantially tangent to the core and converging to the apex of the recess at one end, the other ends of said edges constituting spaced terminals supported in the field of the core 65 whereby, when the magnet is energized it

will exert the maximum pull longitudinally of the armature and unseat the valve.

In testimony that I claim the foregoing as my own, I have hereto affixed my signature.
